CLAIM

The ornamental design for a hair clipper, as shown and described.

DESCRIPTION

FIG. 1 is a front, left, and top perspective view of a hair clipper, showing my design.

FIG. 2 is a rear, right, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 illustrating a design of a blade of the hair clipper; and, FIG. 10 is a partial enlarged view of an area labeled 10 in FIG. 2 illustrating the rear of the handle.

The broken lines shown in the drawings are included for the purpose of illustrating portions of the hair clipper that form no part of the claimed design.
